CLAIM

I claim the ornamental design for an optical disk duplicator, as shown and described.

DESCRIPTION

FIG. 1 shows the front perspective view of an optical disk duplicator showing my new design,

FIG. 2 shows the rear perspective view thereof,

FIG. 3 shows the front view thereof,

FIG. 4 shows the rear view thereof,

FIG. 5 shows the right side view thereof,

FIG. 6 shows the left side view thereof,

FIG. 7 shows the top view thereof; and,

FIG. 8 shows a bottom view thereof.
